SHIP'S FORM

Vladimir Yourkevitch, Paris, France

Application May 21, 1932, Serial No. 612,701

1 Claim. (Cl. 114—56)

This invention relates to ships' forms and is directed more particularly to the modification of existing ships and merchant ships in particular.

The object of the invention is to provide a novel method whereby the hulls of existing ships may be changed or modified in order to increase their speed without necessitating increase in the power plant of the ship.

In my prior patent, No. 1,831,643, issued November 10, 1931, there is disclosed ship construction adapted especially to be incorporated in ships during the building thereof, whereby the maximum efficiency of the power plant in the development of speed may be insured especially in new ships and within the original contemplated overall length thereof.

The primary object of the present invention from a more specific standpoint consists in providing a novel and efficient method whereby the advantages of my former invention may be incorporated in ships already built by modifying the hulls of such ships in order to increase their speed.

Hulls of ships, as heretofore made, may be classified generally into three distinct classes, which are so named because of their particular contour at the waterline, at the forward part of the ship. The first class and that which is almost universally found under present practice is the convex form wherein the fore part of the ship bulges out appreciably at the bow or stem in order to obtain maximum buoyancy in this portion of the ship. The second form may be called a straight form because the sides of the hull extend substantially straight back from the stem of the hull and impart almost a straight wedge shape to the fore part of the hull. The third form may be termed a concave form. This form is almost unknown in merchant marine, but has been attempted in some battleship design, but without any degree of success.

I have found by exhaustive experimentation and research that the concave hull form, if produced in a particular way will give maximum speed. In the past where this form has been attempted, the concave ship has been carried out on a hit or miss theory, and almost invariably the result has been that a greater resistance has been set up to forward motion of the ship due to the lack of any realization of the problems involved or to a definite understanding of the factors confronting this type of construction.

The present invention provides a method whereby ships already built and of which it is desired to improve the performance as compared

with usual practice, may be changed or modified in accordance with well defined principles in order to give a marked increase in speed and without any question as to the results to be obtained.

I have found that this may be accomplished by rebuilding the fore part of the ship and slightly increasing the overall length of a ship sufficiently, however, to give a concave fore part at the waterline so as to obtain a sectional area curve having also a concave curvature of variable radius and moreover characterized by a minimum radius of curvature at a spot corresponding substantially to the abscissa of the center of pressure which is determined in the manner fully described in my prior patent.

In the accompanying drawing, I have shown one illustrative manner of carrying out the present invention and in this drawing:

Figure 1 shows diagrammatically the manner in which the method of this invention is carried out.

According to this invention the trace of this new foreship is obtained in superposing on the existing construction water-line a new water-line, which would be obtained for the same ship in following the procedure described in the main patent; this new waterline is then shifted or slid forward in direction of the ship's longitudinal axis, so as to bring a portion of the new water-line in coincidence with the real water-line of the existing ship; thus shifted, the new waterline determines the contour of the new foreship.

Other advantages and particulars of the invention will be made clear in describing the figure attached hereto. The base line "A—A" of this figure represents the longitudinal axis of a ship which is to be rebuilt according to the present invention. "1" is a horizontal half-section of the existing ship through the construction water-line plane. "2" is a corresponding horizontal half-section through the water-line plane of the same ship, if traced according to the procedure described in the main patent. As explained in the main patent, the frame contours of the trace "2" are narrower than those of the trace "1" in the ship's transversal section which corresponds to the location of the centre of pressure "3", the longitudinal distance of this centre of pressure from the fore perpendicular as measured in meters being determined by the formula:

$$x = \left(\frac{v}{\sqrt{L}} - 1 \right) \frac{L}{4}$$

Wherein:—

X denotes the abscissa of the "center of pressure" in meters measured aft from the stem

- 5 V denotes the designed speed in knots
L denotes the ship's length in meters.

According to the invention the existing fore-ship is cut off and replaced by a new somewhat elongated foreship so as to approach the contour

- 10 "2". This contour "2" of the new foreship is determined in shifting or sliding the contour "2" along the axis "A—A" so as to bring the centre of pressure "3" of the contour "2" in point "4" of the contour "1". Then the contour "2" comes 15 to position "2". It is to be noted that, thus shifted, a portion of the contour "2" comes to coincidence with the contour "1" (between the points "4" and "5"); practically speaking only the portion "5—6" of the contour "2" remains.
- 20 It is also to be noted that the elongation determined as above is very insignificant and increases but very little the ship's length. Nevertheless, thanks to this elongation the same favourable results are achieved as if the vessel were traced according to the procedure of the invention, i. e.
- 25 the resistance to forward motion is considerably reduced, or, otherwise speaking, the bow-wave is diminished. The effect of elongation of the ship's foreship according to the above procedure is to bring the value "α" of the angle of attack of the ship at a certain distance from the bow to a much smaller value "φ" of the same angle according to the invention; this angle is reduced by adoption of a hollower waterline so as to enable the water-30 streams to flow easily past turning round the fore-ship and without being pushed forward by the ship's hull.

- It will be noted from the drawing that the contour 2 at and forwardly of the point 3 is concave 40 and when this is moved forwardly in a direction of

the ship's longitudinal axis so as to bring a portion of the new water line in coincidence with the real water line of the existing ship, the new fore part of the ship will be longitudinally concave at the water line.

Having now particularly described and ascertained the nature of my said invention and in what manner the same is to be performed, I declare that what I claim is:

The method of modifying the fore part of a 10 ship's hull to increase its speed, which consists in making an initial waterline trace of the hull of the ship to be modified, thereupon superimposing upon the initial trace a second waterline 15 trace of concave form starting at the stem of the initial hull trace and extending aft, thereupon moving said second trace forwardly along the longitudinal center line of the hull until the point of the second trace, corresponding to the abscissa X of the center of pressure determined by the 20 formula,

$$X = \left(\frac{V}{\sqrt{L}} - 1 \right) \frac{L}{4}$$

(wherein X equals the distance of the center of 25 pressure measured aft along the center line of the hull from the stem thereof in meters, V the designed speed in knots and L the ship's length in meters), comes into coincidence with the initial trace, both traces becoming substantially 30 tangent in this region, thereupon adding to the forward portion of the initial trace that portion of the forwardly shifted second face which extends from the point of tangency forwardly to the longitudinal center line of the hull to show the added 35 fore section required, thereupon designing upon the forward portion of the hull of the ship which conforms to the initial trace a new fore part corresponding to the said added fore section.

VLADIMIR YOURKEVITCH. 40
